CLAIM

We claim the ornamental design for a bottle, as shown and described.

DESCRIPTION

FIG. 1 is a top perspective view of a bottle showing the new design;

FIG. 2 is a front elevation view thereof, with the back, left, and right elevation views being identical to the front elevation view shown in FIG. 2;

FIG. 3 is a top plan view thereof;

FIG. 4 is a bottom plan view thereof;

FIG. 5 is top perspective view thereof, with the cap exploded from the container;

FIG. 5A is a cross-sectional view taken along line 5A-5A in FIG. 5; and

FIG. 6 is a front elevation view thereof, with the cap exploded from the container;

FIG. 7 is a rear elevation view thereof, with the cap exploded from the container;

FIG. 8 is a right elevation view thereof, with the cap exploded from the container;

FIG. 9 is a left elevation view thereof, with the cap exploded from the container;

FIG. 10 is a top plan view thereof, with the cap exploded from the container; and,

FIG. 11 is a bottom plan view thereof, with the cap exploded from the container.

The broken lines in the drawings illustrate the portions of the bottle that form no part of the claim.
